UNITED STATES PATENT OFFICE.

MILES GANDY, OF CEDARVILLE, NEW JERSEY.

OYSTER-DREDGE CATCHER.

1,117,023.

Specification of Letters Patent. Patented Nov. 10, 1914.

Application filed February 7, 1914. Serial No. 817,250.

To all whom it may concern:

Be it known that I, MILES GANDY, a citizen of the United States, and a resident of Cedarville, Cumberland county, New Jersey, have invented certain Improvements in Oyster-Dredge Catchers, of which the following is a specification.

My invention relates to oyster dredge equipment for use on board oyster boats; and the object of my invention is to facilitate the handling of the dredge on and off the boat, more particularly in launching the dredge from the side of the boat after it has been emptied of the oysters.

My invention comprises a supplemental support for the dredge, which support is so mounted and arranged as to greatly facilitate the launching of the dredge and materially reduce the hard work usually attendant upon this operation.

These and other features of my invention are more fully described hereinafter, reference being had to the accompanying drawings, in which:

Figure 1 is a perspective view of my improved catcher as applied to the side of a boat; Fig. 2 is a sectional view illustrating the manner in which the dredge engages the catcher when brought aboard the boat; Fig. 3, is a view illustrating the position of the dredge after it has been emptied of the oysters and is ready to be launched for a fresh catch, and Fig. 4, illustrates a modification of my invention.

Oyster dredges, as is well known, constitute a rake structure, from which a bag of suitable material extends rearwardly, with a frame which may be substantially triangular in shape extending forwardly; such frame carrying the rake and the bag. After the oysters have been caught, the dredge is, of course, hauled up over the side of the boat, and oyster boats are usually provided with a roller of considerable size, over which the chain and subsequently the dredge frame is drawn.

As ordinarily constructed and as operated, the dredge is dragged over the side of the boat and over the roller until the rear end of the dredge rests upon the roller. The

oysters are then dumped, and in the dumping operation the whole dredge falls to the deck of the boat and requires to be lifted by the men before it can be launched again. This is particularly hard work and is a source of much exhausting labor to the oystermen, and the object of my invention is to obviate this lifting of the dredge, and second, to assist in placing the dredge after the oysters have been emptied in such position that it can be launched by merely pushing it over the side of the boat. For this purpose, I propose to place a second roller or bar, a little smaller than the main roller, disposed inside the same and extending above the main roller, and to mount the second roller or bar in a suitable frame which may be hinged or journaled at a suitable point on the boat, and to provide resilient or spring means whereby the second roller or bar may be moved by such spring means so as to impart slight movement to the dredge after the oysters have been emptied from the same, thereby placing said dredge in a better position for launching and avoiding entirely the necessity of bodily lifting the dredge for the purpose of effecting the launching operation. The spring supporting means for this roller may be of any suitable character, and are so disposed that when they react upon the roller or bar supporting the dredge, or the frame carrying such roller or bar after the weight of the latter has been reduced by the discharge of the oysters, they will not throw said roller or bar out with a jerk, but will effect an easy shifting of the same for the purpose desired.

In the accompanying drawings, 1 represents the side of the boat upon which a main roller 2 is mounted, which roller may be journaled in suitable blocks 3, and 4 is a post around which the dredge chain is hauled when the dredge is taken aboard. This operation is usually performed by a small engine (not shown) having a suitable drum upon which the chain may be wound.

Located inside the main roller 2 and disposed above the same is an element which may comprise a smaller roller or a bar 5, 100

which element is carried by a frame 6, which may be journaled or hinged in brackets 7, and carries a suitable torsion spring 8 whose normal tendency is to keep the roller or 5 bar 5 close up against the roller 2. When the dredge is dragged inboard, it passes up over the main roller 2 and the supplemental roller (or bar) 5 until the teeth 9 of the dredge come over the side, and these catch 10 against the supplemental roller (or bar) 5 in the manner shown in Fig. 2, moving the roller or bar and its frame against the tension of the spring, and preventing the dredge dropping onto the deck. The oysters 15 are now emptied on the deck, and upon the dredge being relieved of this weight, the spring 8 will react and move the dredge outboard a slight distance to the position shown in Fig. 3, so that it only becomes 20 necessary for the men to push it over the rollers 5 and 2 the rest of the distance for proper launching.

The swinging frame 6 is shown as pivotally mounted or hinged at the side of the 25 boat. It will be understood, however, that this structure may be hinged at any convenient point on the boat, so long as it is in proper position with relation to the roller 2 and has proper engagement with the torsion spring to effect retractive movement 30 thereof with the dredge.

It will be understood, of course, that I do not wish to be limited to the particular 35 character of spring supporting means employed, since any form of spring that will yield under the weight of the full dredge and react to move the dredge slightly outboard when the oysters are emptied, may be employed.

40 As noted, I may use a bar instead of the supplemental roller 5, and my claims are intended to cover the use of either or both devices.

In some instances, particularly where the 45 draft of the chain is at a low angle, it may be desirable to dispose the catching means much closer to the main roller 2, and for this purpose I may employ a structure such as shown in Fig. 4, in which a plate or bar 50 5^a with a relatively sharp edge is carried by the frame 6 in lieu of the supplemental roller 5.

In either instance, I prefer a construction that may be moved to such a position 55 as to release the rake of the dredge should the hauling gear bring the latter too far into boat. Under such conditions, the catcher will be forced down against the tension of the spring, and the rake teeth will 60 ride over the roller or be lifted so high from the bar as to ride over the edge of the same; permitting the dredge to fall onto the deck without danger of damaging either the dredge or the catching device.

I claim:

1. The combination of a boat, and a swinging spring supported member carried thereby for engagement by a dredge.

2. The combination of a boat, and a swinging spring supported roller carried 70 thereby for engagement by a dredge.

3. The combination of a boat, a support, a frame for said support pivotally mounted on said boat and movable with respect thereto, said support serving to engage an 75 oyster dredge, and spring supporting means for said support, said spring supporting means serving to shift the roller and dredge outboard when the weight of the dredge is decreased by the discharge of the oysters. 80

4. The combination of a boat, a roller support, a frame for said roller support pivotally mounted on said boat and movable with respect thereto, said roller support serving to engage an oyster dredge, and spring tension means for said roller support, said spring means serving to shift the roller support and dredge outboard when the weight of the dredge is decreased by the discharge 85 of the oysters. 90

5. The combination of a boat, a roller member carried by the same over which an oyster dredge is drawn inboard, a second member disposed inside the roller member and a slight distance above the same, a swinging pivotal support for said second member, and spring means tending to hold 95 said second member against the roller.

6. The combination of a boat, a roller carried by the same over which an oyster dredge is drawn inboard, a second roller disposed inside the first roller and a slight distance above the same, a swinging pivotal support for said second roller, and a torsion 100 spring carried by said support and tending to hold said second roller against the first-named roller. 105

7. The combination of a boat, a roller carried thereby, fixed journals for the same, a pivotally mounted member normally adjacent said roller, and spring means for holding 110 said pivotally mounted member in its normal position.

8. The combination of a boat, a roller carried thereby, fixed journals for the same, a second roller, a pivoted frame in which the same is journaled, and a torsion spring for holding said second roller adjacent the first-named roller. 115

9. The combination of a boat, and a spring-supported member carried thereby for engagement by a dredge; said member being movable to a position to release the dredge. 120

10. The combination of a boat, and a spring supported roller carried thereby for engagement by a dredge; said roller being movable to a position to release the dredge. 125

11. The combination of a boat, a pivotally mounted frame, a spring for holding said frame in a substantially vertical position, and a dredge-engaging member carried by
5 said frame; said member being movable against the tension of said spring to a position to release the dredge.

In testimony whereof, I have signed my name to this specification, in the presence of two subscribing witnesses.

MILES GANDY.
